(57) **CLAIM**

The ornamental design for an enclosure wall, as shown and described.

DESCRIPTION

In a preferred embodiment, the nature of this product is a plumbing fixture primarily useful for retaining water within a bathing area.

FIG. 1 is a left, top, front perspective view of an enclosure wall embodying my new design;

FIG. 2 is a front elevational view thereof;

FIG. 3 is a left side elevational view thereof, the right side elevational view being a mirror image of the left side shown; and,

FIG. 4 is a top plan view thereof.
